CLAIM

The ornamental design for a game board with set of playing cards and game token components, as shown and described.

DESCRIPTION

The patent or application file contains at least one drawing executed in color. Copies of this patent or patent application publication with color drawing(s) will be provided by the Office upon request and payment of the necessary fee.

This invention was made with government support under grant number DMR1830704 awarded by the National Science Foundation. The government has certain rights in the invention.

FIG. 1 is a front perspective view of the game token of the game board with set of playing cards and game token components;

FIG. 2 is a back perspective view thereof;

FIG. 3 is a front view thereof;

FIG. 4 is a back view thereof;

FIG. 5 is a left side view thereof;

FIG. 6 is right side view thereof;

FIG. 7 is a top view thereof; and

FIG. 8 is a bottom view thereof.

FIG. 9 is a top view of the game board of the game board with set of playing cards and game token components; and FIG. 10 is a bottom view thereof.

FIG. 11 is a front view of the first playing card of the game board with set of playing cards and game token components; and

FIG. 12 is a back view thereof.

(Continued)

FIG. 13 is a front view of the second playing card of the game board with set of playing cards and game token components; and

FIG. 14 is a back view thereof.

FIG. 15 is a front view of the third playing card of the game board with set of playing cards and game token components; and

FIG. 16 is a back view thereof.

FIG. 17 is a front view of the fourth playing card of the game board with set of playing cards and game token components; and

FIG. 18 is a back view thereof.

FIG. 19 is a front view of the fifth playing card of the game board with set of playing cards and game token components; and

FIG. 20 is a back view thereof.

FIG. 21 is a front view of the sixth playing card of the game board with set of playing cards and game token components; and

FIG. 22 is a back view thereof.

FIG. 23 is a front view of the seventh playing card of the game board with set of playing cards and game token components; and

FIG. 24 is a back view thereof.

FIG. 25 is a front view of the eighth playing card of the game board with set of playing cards and game token components; and

FIG. 26 is a back view thereof.

FIG. 27 is a front view of the ninth playing card of the game board with set of playing cards and game token components; and

FIG. 28 is a back view thereof.

FIG. 29 is a front view of the tenth playing card of the game board with set of playing cards and game token components; and

FIG. 30 is a back view thereof.

FIG. 31 is a front view of the eleventh playing card of the game board with set of playing cards and game token components; and

FIG. 32 is a back view thereof.

FIG. 33 is a front view of the twelfth playing card of the game board with set of playing cards and game token components; and

FIG. 34 is a back view thereof.

FIG. 35 is a front view of the thirteenth playing card of the game board with set of playing cards and game token components; and,

FIG. 36 is a back view thereof.

The broken lines in the figures depict portions of the game board with set of playing cards and game token components that form no part of the claimed design. The game board with set of playing cards and game token components are of conventional thickness that forms no part of the claimed design.
